UNITED STATES PATENT OFFICE

WILLIAM O. BARNES, OF WORCESTER, MASSACHUSETTS

APPARATUS FOR THE RECEPTION OF RADIO MESSAGES

Application filed December 27, 1926. Serial No. 157,122.

My invention relates specifically to automatic devices for reducing or nullifying the effects on a radio receiving system of the phenomenon called fading, commonly occurring in long distance reception.

While my invention may be usefully employed in the reception of other forms of signals, consisting of high frequency electric waves, it is of special value in the reception of radio telephonic communications. In the following specification, my invention is shown applied in different ways to radio telephonic receivers, but I do not wish to be limited to its application to that particular branch of the art.

The nullification of the effects of fading is accomplished by the employment of a novel regulating device, which automatically combines with each high frequency wave comprising the signal, a regulating wave of similar form and of an intensity determined by the intensity of the signal wave and by the mean intensity of all the waves comprising the signal received during an immediately preceding interval of time, thereby augmenting or diminishing the intensity of each signal wave according as the mean intensity of the waves received during the immediately preceding time interval has been less or greater than a definite intensity. This definite intensity is hereinafter called the critical intensity.

Reference is to be had to the accompanying drawings in which

Fig. 1 is a perspective view of the regulating device, hereafter called the bridge. Figs. 2 and 3 are enlarged views of parts of the bridge shown in section. Fig. 4 is a diagram showing a preferred arrangement of the amplifying stages of a radio receiver and manner of coupling therewith my regulating device. Fig. 5 is a diagram showing an alternative arrangement of the amplifying stages of a receiver and my regulating device. Fig. 6 shows diagrammatically an alternative method of coupling the bridge to the circuits of the receiver. Figs. 7, 8 and 9 are graphical representations of radio signals or waves.

To a suitable insulating base 1, Fig. 1, the four spring sheet metal terminals 2, 3, 4 and

5 are secured by means of the screws. Four resistance elements, R1, R2, R3 and R4 are held in place by the elasticity of the upstanding ears of the terminals and electrically connect the terminals with one another.

Fig. 2 is a sectional view showing the construction of resistance elements R1 and R3. A very thin walled glass tube, 6, of capillary dimensions traverses the interior of a larger glass tube 7. The bore of 6 passes through the closed ends of the tube 7. Suitable metallic closures, such as the amalgam plugs 8 are provided for each end of the bore of 6. The conductor of this element consists of a conducting fluid filling the bore of 6, such as a dilute solution of chloride of potassium; or it may consist of a very thin film of metal such as silver, chemically deposited on the inside of the wall of 6. Hereafter the tube 6 and the enclosed conductor will be referred to as the filament.

The annular space 9, enclosed between 6 and 7 is exhausted of air and is hermetically sealed. The interior of 7 is preferably covered with a film of silver or platinum. This construction is adopted in order to effectually prevent loss of heat by the filament except by conduction into the ends of 7. Under these conditions of thermal insulation, a very minute electric current flowing through the conductor will perceptably raise the temperature of the filament.

If a uniform electric current starts to flow through the conductor of the filament the temperature of the filament will immediately begin to rise and will continue to rise for a certain time until the temperatures of the various parts of the filament have been raised above the temperature of the surrounding air, by certain amounts dependent on the strength of the current. If the strength of the current then changes, the temperatures of all parts of the filament will immediately begin to change toward a new set of values. The extent and promptness of this thermal response of the filament to fluctuations in the strength of the current will depend on the electrical resistance of the conductor, the length and cross section of the filament and the thermal capacity and thermal conductivity of the materials

composing the filament. With a given combination of the different values that may be given to these dimensions, the mean temperature of the filament will be an approximate index of the mean strength of the current during the preceding interval of time and, in general, the prompter the thermal response of the filament to changes in current the shorter will be that interval of time.

Fig. 3 is a sectional view, showing the construction of the resistance elements R2 and R4. 10 is a thick walled glass tube of capillary bore. Suitable metallic closures, such as the amalgam plugs 8, are provided for each end of the bore. The conductor of this element may consist of a suitable conducting fluid filling the bore of 10 or it may be a metallic film deposited on the inside surface of the wall of 10. It is desirable that the material composing this conductor shall have a smaller thermal coefficient of electrical resistivity than the material composing the conductors of R1 and R3, but this is by no means necessary, as the material of all these resistance elements may be the same. The exterior of 10 constitutes a large and efficient thermal radiating surface. The wall of 10 presents a broad and short conducting path for the escape of heat from the conductor to the radiating surface. Consequently, when a current of electricity flows through the conductor of R2 or R4 the resulting rise in temperature is very small as compared to the rise of temperature produced in the conductor of R1 or R2 by the flow therein of an equal current.

The four resistance elements R1, R2, R3 and R4, when mounted as shown in Fig. 1, and a current flows through them between 2 and 4, form a Wheatstone bridge. There will be no difference of potential between 3 and 5 when the product of the resistances of R1 and R3 equals the product of the resistances of R2 and R4.

In practice it is often convenient to make the resistance and other dimensions of R1 equal to those of R3, and the resistance and other dimensions of R2 equal to those of R4, although these equalities are by no means essential. It will aid the clearness of the following description, to assume as I therefor do in the following that these equalities exist.

R1 and R3 are so made that at equal temperatures, they have a slightly lower resistance than R2 and R4. Therefore a current of a certain definite or critical strength flowing through the bridge between 2 and 4 will so raise the temperatures in the conductors of R1 and R3 that they will have the same resistance as those of R2 and R4. Under these conditions the potential at 5 will equal the potential at 3.

If the current is weaker than this critical strength as soon as stable thermal conditions are established, a difference of potential will

exist between 5 and 3, in the same direction as that existing between 2 and 4. The value of the potential difference will be nearly proportional to the difference between the square of the current and the square of the current actually existing. If the current be stronger than critical strength, the potential difference between 5 and 3 will be in the opposite direction to that between 2 and 4.

If the current be a high frequency alternating current of fluctuating value, but of smaller mean value than that called critical, an alternating potential will be set up between 5 and 3 which is in phase with the potential between 2 and 4. The intensity of the wave of potential between 5 and 3, which results from a single alternation of current will be nearly proportional to the product of such current alternation by the difference between the square of the critical current and the mean square of the current during an immediately preceding time interval. In mathematical language, the intensity of the potential wave between 5 and 3 will be an increasing function of the intensity of the potential wave impressed on the bridge, between 2 and 4, and a decreasing function of the mean intensity of the potential wave between 2 and 4, during an immediately preceding time interval. If I construct the bridge of four resistance elements such as is shown in Fig. 2, and make the conductors of R1 and R3 of a liquid which has a large thermal coefficient of resistivity and the conductors of R2 and R4 of silver which has a relatively small coefficient, the result is a working bridge which does not depend on differential emission of heat. A liquid that can be used is chloride of potassium.

In order to describe clearly the manner in which my automatic regulator acts to eliminate the effects of fading in broadcast reception, I will proceed to describe the nature of the phenomenon, fading, with the aid of the graphs, Figs. 7, 8 and 9. In the preparation of these graphs, for the sake of clearness, no attempt has been made to represent the true relative frequencies of the carrier wave, the modulations impressed thereon by the transmitting instrument and of the fluctuations of signal strength which constitute fading.

In the intervals of silence, during telephonic broadcasting, the transmitting instrument will radiate the rapid succession of electrical waves of uniform intensity represented by the sinusoidal line 11, Fig. 7. The intensity or strength of these waves is represented by the distance between the parallel straight lines 12 and 13 drawn through the peaks of 11. When sound affects the transmitter, the waves radiated are modulated, some are increased in intensity and others decreased. The result is illustrated in Fig. 8. The lines 14 and 15 are drawn through

the peaks of 11 are sinusoidal, the frequency of their undulations being the same as the frequency of the sound vibrations affecting the transmitter. If each of the waves of 11 be measured, the means or average intensity of all large groups of successive waves will be found to be practically constant and equal to the distance between the lines 12 and 13 as in Fig. 7.

10 If the intensity of the waves of 11 be measured at a great distance from the transmitter, it will be found that due to some causes operating on the waves during their transmission through space, their average intensity no longer remains constant but fluctuates irregularly over a wide range. The result is illustrated in Fig. 9. The lines 12 and 13 whose relation represents the successive mean intensity of the waves, are no longer straight and parallel but undulate. The ratio, however, between the height of any particular wave, Fig. 9, and the distance between the lines 12 and 13 at that place, or time, is substantially the same as the ratio 25 between the height of the same wave shown in Fig. 8 and the constant distance between the straight lines 12 and 13, which represents the constant mean intensity of the waves, near the transmitter.

30 Consequently if to each of the waves comprising the signal, a regulating wave be added, of like form and frequency, of an intensity proportional to the intensity of the signal wave and of such value as to maintain the 35 mean intensity of the augmented signal nearly constant, the form of the augmented signal will agree closely with that of the signal as originally transmitted.

Fig. 4 illustrates, by means of conventional symbols, one method on incorporating my regulating bridge in a radio broadcast receiver. The signal is collected by the antenna A, from which it passes through two stages to tuned radio frequency amplification, consisting of the vacuum tubes V1 and V2 and their associated circuits. These circuits need no extended description as they are examples of well known and established practice in coupling the various stages of radio frequency amplifier together. Any other known method of coupling these stages may be substituted therefor.

45 The plate current from V2 passes through the inductance L5. This coil is magnetically coupled to the coil L6 and the signal is delivered to the grid of V3. The inductance of choke coil L8 is an efficient barrier to the passage of the alternating component of the plate filament current from V3. Its resistance 50 is sufficiently low, however, to permit the battery B to maintain sufficient potential on the plate of V3 to insure efficient working of the tube. The alternating component of the current passes through condenser C5 and 55 the signal is delivered to the grid of V4. The

alternating component of the plate filament current from V4, unable to pass through the choke coil L9, passes through the condenser C6 and the bridge resistance R1, R2, R3 and R4. It also affects the grid of detector tube 70 V5, through the condenser C7.

The combination of the two tubes V3 and V4 will hereafter be referred to as the regulated amplifying element of the receiver. The input circuits associated with the tubes 75 V3 and V4 of the regulated amplifying element are shown in the drawings as being of the untuned variety, but it is to be understood that any or all of these input circuits may be of the tuned variety.

If the signal as delivered by the tuned radio frequency amplifier is of such intensity, when multiplied by the normal amplifying powers of V3 and V4, as to cause an alternating current of critical strength to flow 85 through the bridge, no potential will be developed between 5 and 3 and the bridge will exert no influence on the intensity of the amplified signal delivered to the grid of the detector. But when the signal sinks below this 90 intensity, an alternating current due to potential between 5 and 3 will flow through the bridge and the inductance coil L7. L7 is magnetically coupled to L6. Hence the current in L7 will cause an augmentation of the 95 signal at the grid of V3. The strength of the current flowing through the bridge, between 2 and 4, will depend on the amplified intensity of the augmented signal, hence its decrease from critical value and the decrease in 100 the intensity of the signal delivered to the detector grid will be less, proportionately, than the decrease in the mean intensity of the incoming signal.

When the mean intensity of the incoming 105 signal increases through critical value to something more than critical value the potential waves between 5 and 3 will decrease in intensity through zero to negative values. The resulting current through 17 will therefore cause the signal at the grid of V3 to be diminished. The strength of the current flowing through the bridge, between 2 and 4, will depend on the amplified intensity of the diminished signal. Consequently the increase 110 of the bridge current between 2 and 4 and the intensity of the signal delivered to the grid of the detector will be smaller, proportionately than the increase in the incoming signal.

The regulated amplifying element, here shown as consisting of two vacuum tubes, may, in fact, be composed of any number of tubes. In general, it is found that the higher the total normal amplifying power of the 115 tubes composing this element, the less will be the fluctuation of mean signal intensity, delivered to the detector grid. The human ear is not very sensitive to moderate fluctuations in the intensity of sound, so that in most cases 120 125 130

satisfactory reception will be obtained with a regulated amplifying element of moderate power.

The selective function of this receiver is shown as performed by two stages of tuned radio frequency amplification. When excessive fading of the signal is to be expected, it is advantageous to employ as many sharply tuned stages as possible.

10 Fig. 5 represents an alternative way of combining the regulated amplifying element with the other parts of the receiver. The parts of this receiver are lettered the same as those in Fig. 4 which perform similar functions. The incoming signal, instead of passing from the tuned amplifying stages through the regulated amplifying element to the detector, passes direct from V2 through condenser C5 to the grid of the vacuum tube V6, thence through condenser C8 to the grid of detector V5. Terminal 2 of the bridge is connected to the grid of V6, terminal 4 to the filament of V2. Terminals 5 and 3 are connected to the ends of coil L7 which is magnetically coupled to L6, the grid coil of V3 the first tube of the regulated amplifying element. Consequently, when the mean incoming signal at 2 is of less than critical intensity, the resulting alternation of potential between 5 and 3 will, acting through V3 and V4 cause an augmentation of the signal at the grid of the detector V5. Likewise, when the incoming signal at 2 is of greater mean intensity than critical value, the resulting potential between 5 and 3 will cause a decrease of signal intensity at the grid of V5.

Fig. 6 is a diagram showing part of a receiver, in which the bridge is coupled to the output of the regulated amplifying element by magnetic induction and the compensating increment is added to the signal through a capacity.

The signal is received at the grid of V3, the first tube of the regulated amplifying element, from the plate of the last stage of tuned amplification, (not shown) through the condenser C8. It passes through the tubes V3 and V4 as previously described. The output current of V4 flows through coil L16, which is coupled magnetically to the coil L17. An alternating current is therefore induced in L17, which flows through the bridge from 2 to 4 and also affects the grid of the detector V5. An alternating current, due to any potential that may be developed between 5 and 3, flows through condenser C9, resistance R7, condenser C10 and the bridge, and in so doing, increases or diminishes the intensity of the signal at the grid of V3, according to whether the mean intensity of the incoming signal is deficient or excessive.

It is obvious, that with the magnetic coupling here shown between the output of the regulated amplifying element and the bridge, I may also employ the magnetic coupling

between the bridge and the input of the regulated amplifying element shown in Figs. 4 and 5.

Carried out in any of the ways shown, it will be seen that this invention provides for compensating for any reduction in the loudness of the reception of radio messages or fading, as it is commonly called. This results in the practically instantaneous increase in the loudness of reception which, whether entirely compensating for the fading or not, will greatly improve the reception. Incidentally it also cuts down particularly loud reception and makes the whole message more uniform in this respect. It is particularly adaptable for radio telephonic messages but is of value in all kinds of radio receiving.

Although I have illustrated and described certain forms of apparatus and diagrams of wiring I am aware of the fact that the invention is not limited to these particular features and that they can be modified by any person skilled in the art without departing from the scope of the invention as expressed in the claims. Therefore I do not wish to be limited in these respects but what I claim is:—

1. In a receiving device for signals transmitted in the form of electric waves, the combination with means for receiving the waves and a regulated amplifying element, of four resistances connected together in the form of a Wheatstone bridge, two opposite terminals of said Wheatstone bridge being connected with a receiving circuit, the other two opposite terminals being connected with the amplifying element to vary the intensity of the currents therein, the opposite resistances in each case being constructed to heat up at different rates under the influence of electric current and thus change their relative resistance, the four resistances constituting means whereby when the intensity of the receiving current decreases the intensity of the currents through the amplifying element will increase and vice-versa.

2. In a receiving apparatus of the class described, an amplifying element, an output circuit of the amplifying element composed in part of a thermally variable resistance so related to other parts of the circuit, that each signal wave, in passing through the circuit, will generate between two points of the circuit, a potential wave of a form substantially similar to the signal wave and of an intensity determined by the intensity of the signal wave and the mean intensity of the signal waves received during an immediately preceding time interval.

3. In a receiving apparatus of the class described, an amplifying element, an input circuit of the amplifying element composed in part of a thermally variable resistance so related to the other parts of the circuit, that each signal wave, in passing through the cir-

cuit, will generate, between two points of the circuit, a potential wave of a form substantially similar to the signal wave and of an intensity determined by the intensity of 5 the signal wave and the mean intensity of the signal waves received during an immediately preceding time interval.

4. A method of controlling the reception of signals composed of electric waves, which 10 consists of causing such wave of the signal to effect the generation of a wave of potential of like form to the signal wave and of an intensity determined by the mean intensity of the signal waves received during an im- 15 mediately preceding time interval and combining the generated wave with the signal wave.

In testimony whereof I have hereunto
affixed my signature.
